UNITED STATES PATENT OFFICE

ARTHUR B. MODINE, OF RACINE, WISCONSIN, ASSIGNOR TO MODINE MANUFACTURING COMPANY, OF RACINE, WISCONSIN, A CORPORATION OF WISCONSIN

HEATING DEVICE

Application filed June 20, 1929. Serial No. 372,359.

My invention relates to household heating apparatus and particularly to household heating apparatus which may be installed in the walls of houses or other buildings.

5 The invention has among its other objects the production of apparatus of the kind described, which is compact, convenient, durable, reliable, and highly satisfactory for its intended purpose.

10 A further object of the invention is the provision of improved apparatus of the kind described, which is adapted to be installed in prebuilt walls and also in walls under process of construction.

15 A still further object of the invention is the provision of improved apparatus of the kind described, which is readily accessible for repairs, cleaning, or renewal of parts, and which is easily installed or dismantled.

20 Still another object of the invention is the provision of apparatus of the kind described, which may be removed from its concealed mounting without tearing out any portion of the wall in which it is positioned.

25 Many other objects and advantages of the construction herein shown and described will be obvious to those skilled in the art from the disclosure herein given.

To this end, my invention consists in the 30 novel construction, arrangement, combination of parts herein shown and described and more particularly pointed out in the claims.

In the drawings wherein like reference characters indicate like or corresponding 35 parts:

Fig. 1 is a front elevational view of one embodiment of my invention as it appears when installed in a wall of a room;

Fig. 2 is a section along the line 2—2 of 40 Fig. 1;

Fig. 3 is a section along the line 3—3 of Fig. 1;

Fig. 4 is a transverse vertical section 45 through a modified form of my invention, and

Fig. 5 is a horizontal section along the line 5—5 of Fig. 4.

Referring now more particularly to the drawings, the numeral 10 generally designates a heat exchange device installed in a

wall 11 between spaced apart studding 9. The device includes a radiator unit comprising oppositely positioned header tanks 12 connected by horizontally extending tubes 13. Besides the radiator unit the device includes a housing comprising a wall plate 30 and a front wall plate 19. The wall plate 30 has its upper back portion curved outwardly to deflect the upwardly travelling heated air currents coming from the radiator unit.

The front wall plate 19 has inwardly turned flanged edges suitably formed to adapt the plate to fit into an aperture provided for that purpose in the wall to permit easy removal of the plate when it is desired to gain access to the interior of the device.

The plate 19 preferably extends down to the top of a base board 17 and its ornamental effect is enhanced by the provision of a plurality of vertically extending upper apertures 20, preferably in alignment with a plurality of lower apertures 21. The primary purpose of the apertures 20 and 21 is to provide upper and lower grilles as outlets 75 and inlets, respectively, for air passing through the device.

The wall of the room is shown as having a coat of plaster 26 bonded with laths 27. The wall is apertured to provide a mounting 80 for the plate 19. A base board 17 is positioned at the bottom of the aperture in the wall. The junction of the board 17 with flooring 25 is covered by a quarter round 18.

The plate 30 is positioned in close proximity to a back wall 28 to provide sufficient space between plates 19 and 30 for installation of the radiator unit.

The device is supplied with heating fluid 90 through a feed pipe 14 suitably connected with one of the header tanks 12. The fluid, after passing from the tank 12 through the tubes 13 into the other header tank 12, is discharged through an outlet pipe 16. The flow of fluid through the feed pipe 14 is controlled by a valve 15 and for this purpose an aperture 23 is formed in the base board 17 for the insertion of a key to actuate the valve.

The header tanks 12 stop short of the upper apertures 20 and extend substantially to 100

the bottom of the device. The tanks 12 are elongated transversely of the wall and have a depth substantially equivalent to the wall thickness. The tubes 13 are the usual elliptical cross sectioned type and are arranged in a row starting at the upper front portion of the tanks 12 and extending diagonally downward to the rear portion of the bottom ends of the tanks. The space thus provided below the tubes 13 permits easy access to the feed pipe 14 and to the discharge pipe 16 for cleaning, renewal, or repairing.

The air to be heated passes through the grille formed by the lower apertures 21 and then between the tubes 13 from which it travels upwardly, escaping through the grille formed by the upper apertures 20. The tubes 13 have a generally horizontal direction and are arranged with their cross section out of parallel. As a result of this arrangement, air traveling from the lower grille between the tubes 13 is dispersed equally through the space above the radiator unit and in traveling between the tubes is forced to change its direction, thereby tending to retard the flow and to bring the air into closer contact with the heated tubes than would be the case if the spaces between the tubes were arranged to permit unretarded flow of air. The exchange of heat is further increased by a plurality of fins 22 through which the tubes 13 project. This change of direction of the air currents besides tending to retard the rapidity which the flow would otherwise pass, creates a turbulence conducive to more complete transfer of heat to the air.

A baffle plate 35 serves to direct the traveling currents of heated air towards the top outlet apertures 20. The upper curved portion of the plate 30 directs the air outwardly through the apertures 20, above and below a humidifying tank 33. The tank 33 is replenished by water through a trough 34 which is slidably mounted on the front edge of the tank. The trough 34 projects through the grille formed by the upper apertures 20 and is provided with a flange 36 on its outer exposed end. The flange 36 permits the trough to be pulled outwardly to provide a conduit through which water is poured to replenish the tank 33. A damper 31 is suitably mounted a short distance above the uppermost of the tubes 13, the damper 31 operable by a handle 32 to close the passage and prevent the travel of air through the device.

In Figs. 4 and 5 I have shown another embodiment of the invention installed in a wall 11 comprising oppositely positioned header tanks 47 connected by tubes 48. This embodiment of the device differs from that already described in that the radiator unit made up of the tanks 47 and the tubes 48 is positioned vertically and adjacent to the

outer wall of the device with the spaces between the tubes parallel and inclined upwardly. A flange plate 57 similar to plate 19 of the embodiment previously described is provided to snugly fit in the apertured wall. A plurality of upper vertically extending apertures 58 and of lower vertically extending apertures 59 provide upper and lower grilles respectively. Air in traveling through the lower apertures 59 comes into direct contact with the tubes 48 and is deflected upwardly by reason of the inclination of the tubes. Heating of the air currents is further accelerated by a plurality of fins 49.

Heating fluid is supplied to the radiator unit by a feed pipe 50 which discharges into one of the header tanks 47. The fluid then travels through the tubes 48 into the other of the tanks 47 and escapes through an outlet pipe 52. A valve 51 controls the flow of fluid into the device through the inlet pipe 50. An aperture 53 in the base board 17 permits the insertion of a key for the purpose of opening or closing the valve 51. A back plate 54, end plates 63 and a top plate 64 together with the front plate 57 provide a housing in which the heating apparatus is positioned.

A damper 55 operable by a handle 56 is provided to check the upwardly rising currents of heated air. A humidifying pan 60, positioned in the upper part of the device, has an upwardly and outwardly curved bottom plate 62 positioned to deflect the upwardly traveling currents of heated air through the apertures 58.

The humidifying pan 60 is replenished by means of a trough 61 slidably mounted on the front edge of the pan. The trough 61 has one end projecting through the upper grille. The projecting end of the trough 61 is provided with a flanged handle 65. When it is desired to replenish the water supply in the pan 60 the trough 61 may be moved outwardly a slight distance by pulling on the flange 65 and the trough be used as a conduit into which water is poured and carried to the pan.

Having thus described my invention, it is obvious that various immaterial modifications may be made in the same without departing from the spirit of my invention; hence, I do not wish to be understood as limiting myself to the exact form, construction, arrangement, and combination of parts herein shown and described or uses mentioned.

What I claim as new and desire to secure by Letters Patent is:

1. In a device of the kind described, a housing having a removable front wall plate, a radiator unit having horizontally arranged tubes positioned in the lower portion of the housing, an outlet grille in the upper end of the front wall plate, and an inlet grille in the lower end of the front wall plate adjacent

- to and extending substantially the full height of the radiator, said radiator providing means for directing heated air inwardly and upwardly relatively to the housing.
- 5 2. In a device of the kind described, a housing having a removable front wall plate, a radiator unit having horizontally arranged tubes elongated in cross section positioned in the lower portion of the housing, said plate having an outlet grille in its upper end and an inlet grille in its lower end, said inlet grille being adjacent to and extending substantially the full height of the radiator, said housing being positioned in the wall of a room with said front plate in substantial alignment with the wall surface, said radiator providing means for directing heated air inwardly and upwardly relatively to the housing.
- 10 3. In a device of the kind described, a housing having a removable front wall plate, a radiator unit positioned in the lower portion of the housing, said plate having an outlet grille in its upper end and an inlet grille in its lower end, said inlet grille being adjacent to and extending substantially the full height of the radiator, said housing being positioned in the wall of a room with its front plate in substantial alignment with the wall surface.
- 15 4. In a device of the kind described, a housing having a removable front wall plate, a radiator unit positioned in the lower portion of the housing, said plate having an outlet grille in its upper end and an inlet grille in its lower end, said inlet grille being adjacent to and extending substantially the full height of the radiator, said radiator unit having its upper end adjacent said front wall plate and its lower end adjacent the rear wall of the housing.
- 20 5. In a device of the kind described, a housing having a removable front wall plate, a radiator unit positioned in the lower portion of the housing, said plate having an outlet grille in its upper end and an inlet grille in its lower end, said inlet grille being adjacent to and extending substantially the full height of the radiator, said radiator unit having its upper end adjacent said front wall plate and its lower end adjacent the rear wall of the housing.
- 25 6. In a device of the kind described, a housing, a radiator unit positioned in the lower portion of the housing, comprising oppositely positioned tanks connected by horizontally extending flat tubes, the spacing between said tubes being inclined to the vertical, said housing having a removable front wall plate, said plate having an outlet grille in its upper end and an inlet grille in its lower end, said inlet grille being adjacent to and extending substantially the full height of the radiator unit, said housing being positioned in the wall of a room with its front plate in substantial alignment with the wall surface.
- 30 7. In a device of the kind described, a housing having a removable front wall plate, a radiator unit positioned in the lower portion of the housing, said unit including tubes arranged at an incline to the vertical and being arranged in divergent relation to each other, said plate having an outlet grille in its upper end and an inlet grille in its lower end, said inlet grille being adjacent to and extending substantially the full height of the radiator, said housing being positioned in the wall of a room with its front plate in substantial alignment with the wall surface.
- 35 8. In a device of the kind described, a housing having a removable front wall plate, a radiator unit positioned in the lower portion of the housing, said radiator being composed of oppositely arranged tanks, and tubes connecting said tanks, each of said tanks providing a wall of said housing, said removable front wall plate having an outlet grille at its upper end and an inlet grille at the lower end, said radiator being located at said lower grille and being substantially the same height as said lower grille.
- 40 9. In a device of the kind described, a housing having a removable front wall plate, said plate having an air inlet grille and an outlet grille, the air inlet grille being located adjacent the bottom of said front plate, and a radiator unit located at the inlet grille and extending from between said grilles to beyond the lower end of said inlet grille.
- 45 10. In a device of the kind described, a housing having a removable front wall plate, a radiator unit positioned in the lower portion of the housing, an outlet grille in the upper end of the front wall plate and an inlet grille in the lower end of the front wall plate adjacent to and extending substantially the full height of the radiator, said radiator providing means for directing heated air inwardly and upwardly relatively to the housing, the upper end of the radiator being provided with means for directing air toward the outlet grille provided in the upper end of the front wall plate, said means for directing the air through the outlet grille providing a wall of a tank providing a humidifier.
- 50 11. In testimony whereof, I have hereunto signed my name.
- 55 12. ARTHUR B. MODINE.
